UNITED STATES PATENT OFFICE.

JOSEPH I. LINER, OF CLOSTER, NEW JERSEY, ASSIGNOR TO THE COSTIMETER COMPANY,
OF DETROIT, MICHIGAN, A CORPORATION OF MICHIGAN.

PROGRAM DEVICE.

1,321,112.

Specification of Letters Patent. Patented Nov. 11, 1919.

Application filed September 5, 1918. Serial No. 252,753.

To all whom it may concern:

Be it known that I, JOSEPH I. LINER, formerly a subject of the Emperor of Austria-Hungary, having declared my intention of becoming a U. S. citizen, and residing at Closter, in the county of Bergen and State of New Jersey, have invented certain new and useful Improvements in Program Devices, of which the following is a specification.

This invention relates to program devices, for controlling the operation of recording machines such, for example, as those commonly termed costimeters. The object of my invention is to provide an improved organization of parts in a machine of this character by means of which a costimeter or the like can be made to measure and record time and costs according to different scales of wages or rates of reckoning. A further object is to provide an improved construction according to which a costimeter may be operated under one scale for a certain period of time and then automatically controlled to operate under another scale during another period. Heretofore at the end of a shift or of a day's work, or at the end of a working period which is to be followed by another period in which the wage scale is different, it has been customary to stop the clock for a short time to permit suitable arrangements to be made for the period to follow. Under these conditions, the time recorded on the card of a workman who continues to work from one period into another, does not tally with the actual time which said workman has put in so that it has been necessary for the bookkeeper to make special entries to cover up the discrepancies. With a view to overcoming these objections the present invention contemplates suitable and efficient means for automatically arresting the operation of the costimeter or other time recording instruments during certain predetermined periods referred to above, said means being adapted to automatically make up the deficiency by correspondingly advancing the costimeters or other time recording instruments to balance the reckoning. Other and further objects will appear in the specification and claims.

In the drawings,

Figure 1 is a front elevation of my improved program device;

Fig. 2 is a rear elevation of the same; 55

Fig. 3 is a top plan of the same;

Fig. 4 is a wiring diagram;

Fig. 5 is a plan view of one form of controlling web or band;

Fig. 6 is a plan view of another form of 60 said web or band;

Fig. 7 is a detail front elevation of the gear train for operating the day change.

According to the embodiment of my invention shown on the drawings, a relay 65 magnet 1 receives its energy from a source (not shown) under the control of a master clock, said magnet operates upon an armature 2, carried by the lower arm 3 of a lever, which is pivoted at 4 on a fixed frame, 70 the other arm of said lever having pivotally connected at 5 a pawl 6, which operates a ratchet 7, keyed to a shaft 8, which is journaled in the plate or frame 9. Also keyed to the shaft 8 is a contact operating wheel 75 10 which is provided with ratchet teeth 11, for periodically engaging and operating a plurality of multiple units contacts, which are spaced circumferentially of the ratchet. Each of these contacts comprises a block 12 80 of insulating material carried by pin or stud 13, a shorter leaf 14 and a long leaf 15, secured to said block, and a pair of contact plates 16 mounted on the shorter leaf and overreaching the long leaf of said contact. 85 As shown in Fig. 2, the lower contact is in position in which the long leaf hangs upon one of the teeth 11, while the shorter leaf has dropped to make a contact between said leaves. The mechanism is so timed as to 90 make each operation of one of the multiple units contacts, cover a period of time which includes one or more operations of the units contact 40, 41. A drum 17, of conducting material, is also keyed to the shaft 8, and is provided with radially projecting pins 18 which are adapted to engage in suitable holes 19, in a controlling web or band 20 95 or 21, such as shown in Figs. 5 and 6. The band 20 is moved in the direction of the arrow, shown in Fig. 2 by means of the drum 17 and passes around a slack take-up 100

roll 22 carried by an oscillatory arm 23 and a plurality of guide rolls 24, which are journaled at suitable points. The forward end of the shaft 8 carries an hour hand 25 and 5 a minute hand 26, to indicate time of day. As shown in Fig. 7, a gear 27, which is keyed to the shaft 8, meshes with a pinion 28, which is solid with a gear 29, which in turn meshes with a pinion 30, for driving a 10 minute hand, the ratio being twelve to one. A gear 31, journaled on a pin 32 meshes with the gear 27 and carries a pin 33, which, at every revolution of the gear 31, engages a tooth 34 of a star wheel which is keyed 15 to a shaft 35 for rotating a drum 36 provided with peripheral contact segments 37 and 38. By means of this construction, and by a proper arrangement of contacts on the drum 36, the operating circuits may be controlled 20 in the manner to be hereinafter pointed out for producing different series of impulses to be transmitted to time recording mechanisms, such as costimeters.

Referring to Fig. 1, an insulating block 39 carried by armature lever 3, serves to mount a contact 40, which co-operates with a fixed contact 41. This contact is operated periodically to indicate units of time. As shown in Fig. 4, the fixed contact 41 is connected by a wire 42 to the long contact leaf 15, of each of the hereinbefore referred to contacts. The shorter leaf 14 of each of said contacts is connected by a wire 43 to a brush 44 which is adapted to slidably contact with 35 the drum 17 whenever permitted to do so. Another brush 45 is connected by a wire 46 with the terminal 47 of the program machine, said terminal being connected by a wire 48 to one pole of a battery 49, the other 40 pole of said battery being connected by a line wire 50 to a plurality of costimeter operating coils 51, which, in the present embodiment, are connected abreast between the line wire 50 and another wire 52, which leads 45 to the other terminal 53 of the program machine. A shorter leaf 14 of the lower contact is connected by a wire 54 to a brush 55, which, together with a second brush 56, contacts with the contact 38 on drum 36. The 50 brush 56 is connected by a wire 57 to a brush 58, which is also adapted to bear on the drum 17 whenever it is uncovered. An upper branch wire 50, which leads from the wire 54 is connected to a brush 60, which 55 operates with another brush 61. The latter brush is connected by a wire 62 with a brush 63, which is adapted to co-operate with the drum 17. When desired, another brush 64 may be employed to run on the drum 17, 60 this brush being connected by a wire 65, to an audible signal 66, which is connected by a wire 67, to one pole of the battery 49. By reference to Figs. 5 and 6, it will be seen that the bands or webs 20 and 21 are provided 65 with a series of holes or openings 68,

69, 70, 71 and 72. That shown in Fig. 5 is provided with an additional opening 73.

The operation of my improved program device will now be readily understood and, briefly described, is as follows:

At each energization of the magnet 1, the pawl 6 advances ratchet 7, one tooth, the consequent movement of the shaft 8 drives the ratchet wheel 10 in counter-clockwise direction, so that the contacts shown in the 75 upper right hand corner of Fig. 2 are successively operated. While this operation goes on, the brushes 45, 44, 58 and 63 are in contact with said drum whenever the band or web 20, for example, permits them to be. According to Fig. 4, the brushes 44 and 45 are in contact with the drum, the brush 44 being in register with an elongated opening in the web. Under these conditions, at the next operation of the upper contact when 80 the leaves 14 and 15 are closed, the instantaneous closing of contacts 40 and 41 sends an impulse from battery 49 through wire 50, coils 51, wire 52, terminal 53, contacts 40, 41, wire 42, upper contact 14, 15, wire 85 43, brush 44, drum 17, brush 45, wire 46, terminal 47, wire 48 to battery 49. This results in a certain predetermined step movement imparted to each of the costimeters 51. Should at the same time as the brushes 90 44 and 45 are in contact, openings appear which permit the brush 58 to contact with said drum the lower contact of Fig. 2 would be closed shortly after the upper one had been closed. Under these conditions, in addition to the impulse just mentioned, an additional impulse would be sent to the costimeters over a similar circuit, so that an additional movement would be imparted to each of the costimeters over and above that 95 contemplated by the closing of the first or upper contact. Such a web or band may, therefore, be employed when the operation of the program device is to change its scale from time to time and one-quarter or time 100 and one-half as may be the case in overtime charges. This arrangement is readily met by the arrangement of the slots or openings in the band or web. As indicated in Fig. 5, an opening 73 may be provided to 105 operate with a contact (not shown) which, by establishing a circuit similar to that already pointed out can be made to co-operate with an additional contact arranged adjacent the gear wheel 10, to produce an additional step to the movement for a relatively short period for the purpose of making up a non-productive period, such as that which ordinarily occurs between the ending of one job and the commencement of the next. 110 According to Fig. 4 the drum 36 has been moved by the gear train 27, 31 and 33 into a position in which the brushes 60 and 61 are inactive, so that any slots which permit contact between the brush 63 and the drum 115 120 125 130

17 will be ineffective until such time as the brushes 60 and 61 come into sliding contact with the contact 37 carried by the drum 36. By this means the scale of movement 5 can be changed from day to day or from time to time in the manner already indicated.

I claim:

1. In a system for controlling the operation of time recording instruments, an energizing circuit including a contact device which is periodically actuated to close said circuit, and a multiple period contact device in circuit with the first mentioned contact device, said multiple period contact device remaining open throughout a period including one or more successive actuations of the first mentioned contact device and closed throughout a period including one or 20 more other successive actuations of the first mentioned contact device.

2. In a system for controlling the operation of time recording instruments, an energizing circuit including a contact device which is periodically actuated to close said circuit, and a plurality of multiple period contact devices in circuit with the first mentioned contact device, each of said multiple period contact devices remaining open 25 throughout a period which includes one or more successive actuations of the first mentioned contact device and closed throughout a period including one or more other successive actuations of the first mentioned contact device.

3. In a system for controlling the operation of time recording instruments, an energizing circuit including a contact device which is periodically actuated to close said circuit, and a plurality of multiple period contact devices in circuit with the first mentioned contact device, each of said multiple period contact devices remaining open 40 throughout a period which includes one or more successive actuations of the first mentioned contact device and closed throughout a period including one or more other successive actuations of the first mentioned contact device, and a branch circuit including a contact device for closing a circuit through the first mentioned contact device independently of said multiple contact device.

4. In a system for controlling the operation of time recording instruments, an energizing circuit including a contact device actuated at relatively short periods and a plurality of contact devices in parallel with each other and actuated at relatively longer 55 periods, and means for actuating said longer period contacts independently of each other.

5. In a system for controlling the operation of time recording instruments, an operating circuit for one or more of said instruments, said operating circuit including

a unit period contact, a multiple period contact, and means for actuating said contacts independently of each other each actuation of said multiple period contact serving to close the circuit for a number of actuations 70 of said unit period contact.

6. In a system for controlling the operation of time recording instruments, an operating circuit for one or more of said instruments, said operating circuit including 75 a unit period contact, a multiple period contact, and means for actuating said contacts independent of each other each actuation of said multiple period contact serving to close the circuit for a number of actuations 80 of said unit period contact, said system being provided with means for opening and closing said circuit at another point for periods of time including one or more periods of the multiple period contact.

7. In a system for controlling the operation of time recording instruments, an energizing circuit including a contact device actuated at relatively short periods and a plurality of contact devices in parallel with 90 each other and actuated at relatively longer periods, and means for actuating said longer period contacts independently of each other, said system being provided with means for selectively controlling the parallel branches 95 of said energizing circuit which include said multiple period contacts respectively.

8. In a system of the character described, the combination with a time recording instrument, of an energizing circuit therefor 100 including a short period contact, long period contacts in parallel with each other and respectively in series with said short period contact, a plurality of brushes for selectively opening and closing said energizing circuit 105 for including one or more of said multiple period contacts, and means for operating said contacts and brushes.

9. In a system of the character described, the combination with a time recording instrument, of an energizing circuit therefor including a short period contact, a plurality of long period contacts in parallel with each other and respectively in series with said short period contact, a plurality of brushes 115 for selectively opening and closing said energizing circuit for including one or more of said multiple period contacts, means for controlling the operation of said brushes singly and in groups, and means for operating said contacts.

10. In a system of the character described, the combination with a time recording instrument, of an energizing circuit therefor including a short period contact, a plurality 125 of long period contacts in parallel with each other and respectively in series with said short period contact, a plurality of brushes for selectively opening and closing said energizing circuit for including one or more 130

- of said multiple period contacts, means for operating said brushes in groups and means for changing said groups to include different branches of the main energizing circuit.
- 5 11. In a system of the character described, the combination with a time recording instrument, of an energizing circuit therefor including a short period contact, a plurality of long period contacts in parallel with each other and respectively in series with said short period contact, a plurality of brushes for selectively opening and closing said energizing circuit for including one or more of said multiple period contacts, a branch circuit provided with a signal, and means for selectively connecting up said multiple period contacts and said signal in said main energizing circuit.
- 10 12. In a system of the character described, a periodically operated contact for indicating units of time, multiple time units contacts arranged in parallel with each other and each in series with said unit contact, a rotary conducting drum, a web or band moving over said drum and provided with different series of perforations therein, brushes arranged to contact with said drum through said perforations, one of said brushes being connected to each of said multiple contacts, an instrument to be operated, and an energizing circuit for said instrument provided with branch circuits for including said multiple units contacts separately in series with said unit contact and instrument to be operated through said brushes.
- 15 13. In a system of the character described, a periodically operated contact for indicating units of time, multiple time units contacts arranged in parallel with each other and each in series with said unit contact, a rotary conducting drum, a web or band moving over said drum and provided with different series of perforations therein, brushes arranged to contact with said drum through said perforations, one of said brushes being connected to each of said multiple contacts, an instrument to be operated, an energizing
- 20 circuit for said instrument provided with branch circuits for including said multiple units contacts separately in series with said unit contact and instrument to be operated through said brushes, and means for changing the energizing circuit to connect and disconnect said brushes independently of said web or band.
- 25 14. In a system of the character described, a periodically operated contact for indicating units of time, multiple time units contacts arranged in parallel with each other and each in series with said unit contact, a rotary conducting drum, a web or band moving over said drum and provided with different series of perforations therein, brushes arranged to contact with said drum through said perforations, one of said brushes being connected to each of said multiple contacts, an instrument to be operated, an energizing
- 30 circuit for said instrument provided with branch circuits for including said multiple units contacts separately in series with said unit contact and instrument to be operated through said brushes, and means for changing the energizing circuit to connect and disconnect said brushes independently of said web or band.
- 35 15. In a system of the character described, a periodically operated contact for indicating units of time, multiple time units contacts arranged in parallel with each other and each in series with said unit contact, a rotary conducting drum, a web or band moving over said drum and provided with different series of perforations therein, brushes arranged to contact with said drum through said perforations, one of said brushes being connected to each of said multiple contacts, an instrument to be operated, an energizing
- 40 circuit for said instrument provided with branch circuits for including said multiple units contacts separately in series with said unit contact and instrument to be operated through said brushes, and means comprising a drum with contacts and other brushes connected up between the first mentioned brushes and said multiple units contacts.
